IMPROVEMENT IN MACHINES FOR CUTTING BUNGS.

JOHN E. SMITH, OF BUFFALO, NEW YORK.

Letters Patent No. 60,272, dated December 4, 1866; antedated November 16, 1866.

SPECIFICATION.

TO ALL WHOM IT MAY CONCERN:

Be it known that I, JOHN E. SMITH, of Buffalo, in the county of Erie, and State of New York, have invented certain new and useful Improvements in Machines for making Plugs and Bungs; and I do hereby declare that the following description thereof is sufficiently clear and exact to enable others skilled in the art to make and use the same, reference being had to the accompanying drawings, making a part of this specification, in which—

Figure 1 is a perspective view.

Figure 2, a longitudinal section through one of the cutters, showing the manner in which the parts are held together.

Figure 3, a plan view of the ring for holding the knives in place.

Figure 4 is a similar view of a nut or ring for the same purpose.

Figure 5 represents a plan of one of the cutters, showing the ends of the knives, and also the inside of the cutter.

Figure 6 is a view of one of the knives for shaving off or tapering the plugs or bungs.

The nature of my invention consists in—

1. The manner of fastening the various parts of the cutter together, and in the employment of a bolt and spring to throw the plugs and bungs out when finished.

2. In the shape of the knife for tapering by means of which a sliding cut is given, thereby giving a smooth, clean surface to the plugs, and a tapering or conical form; also, in the arrangement by which said knife is adjusted to cut any thickness of shaving desired.

3. In the combination of two or more cutters when used in a machine for making plugs and bungs, and in making said cutters, and the spindles to which they are attached, adjustable horizontally, for the purpose of placing them nearer together or farther apart, so that different-sized cutters may be used.

The same letters in the several figures represent similar parts in each.

In fig. 1, A and F represent the counter-shaft and driving pulleys, B the frame by which it is supported; G' is a belt running from the pulley A to one of the pulleys marked G; there are as many of the belts G' as there are of the pulleys G to be driven; said pulleys are fastened to the spindles marked D, to which the cutters C C C C are fastened by set-screws, one of which is shown in fig. 1, and marked V. The spindles run in the boxes marked E, which are made in the usual way of iron, brass, or other suitable material; these boxes have grooves in the bottom which are made to fit upon the ways, X X, along which they can be moved horizontally; they are fixed firmly in place by means of screws or the equivalent thereof, which work under the blocks marked H. In using large or small cutters it is necessary to adjust the spindles, D, horizontally, near together or far apart, according to the size of the cutters. The spindles and cutters are constructed of cast steel. In fig. 2, the letters, I I, represent a section of the knives, showing the way in which they are held in place. T is a groove, of which there is one in each cutter; a front view is shown in fig. 6. On the tube N, is a flange or ring projecting outward and surrounding it; it is marked L. In putting the cutter together, the grooves, T, in the knives are made to fit over the projection or ring L; the ring J is then put on and slipped over the knives, which are made a little tapering where said ring fits over them, so that when the nut, K, is screwed up against it, the knives are held firmly in place. The nut K is moved by a wrench, as shown in fig. 4. The plugs are cut by pressing a board of the proper thickness against the cutters, C, until they cut their way through it. The bolt O, in the meantime, is forced in against the spiral spring, R, as the plug is being cut, but springs out again when the pressure is taken off, throwing the plug out with it. I' represents the knife for shaving off and tapering the plug; it is fitted on to the tube, N, in the same manner as the rest of the knives, but the surface of said tube, and the projection or flange, L, is made to incline slightly inward toward the centre, as shown at W, in fig. 5, so that said knife may be adjusted to cut any thickness of shaving desired, which is done by moving or sliding it around the said tube, N, either to or from the point shown at W, and then tightening it with the nut, K, as before shown; it also allows the knife to be adjusted after it is worn by grinding or sharpening.

I not claim the combination of a number of cutting instruments for boring holes, as that has been done by a number of augers or drills combined.

But what I do claim as my invention, and desire to secure by Letters Patent, is—

The ring J, and nut K, in combination with the groove T, and the flange or ring L, when constructed as and for the purposes described.

JOHN E. SMITH.
